Primary Examiner — Mojtaba Tehrani(74) *Attorney, Agent, or Firm* — Larson & Larson; Justin P. Miller(57) **CLAIM**

The ornamental design for a butt stock plate, as shown and described.

DESCRIPTION

FIG. 1 is a perspective view of a butt stock plate showing the new design;

FIG. 2 is a front elevation view thereof;

FIG. 3 is a back elevation thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines depicting holes in FIGS. 1, 2, and 3 are for the purpose of illustrating the unclaimed portions of the article and form no part of the claimed design.

1 Claim, 7 Drawing Sheets(56)
